M. E. NO. 110 ^{Inventor}

By Frank Macey, Attorney.

UNITED STATES PATENT OFFICE.

MICHAEL E. MALLO, OF GREELEY, COLORADO.

CARBURETER.

1,009,252.

Specification of Letters Patent. Patented Nov. 21, 1911.

Application filed November 26, 1910. Serial No. 594,392.

To all whom it may concern:

Be it known that I, MICHAEL E. MALLO, citizen of the United States, residing at Greeley, in the county of Weld and State of Colorado, have invented certain new and useful Improvements in Carbureters, of which the following is a specification:

My invention relates to carbureters for explosive engines and the object of my invention is the provision of an extremely simple carbureter which does away with the use of spring-actuated valves and also eliminates the necessity of using an air valve and which is therefore easy to clean and to keep in order.

A further object is to provide a carbureter which because of its construction need not be removed from the engine in order to be cleaned and the internal parts repaired.

20 A further object is to provide a novel means for mixing the gasoline with the air previous to the mixture being drawn into the engine.

A still further object is to provide a carbureter in which all of the internal parts may be removed for cleaning or for repair by simply removing the cap of the carbureter.

My invention is shown in the accompanying drawings wherein:

Figure 1 is a vertical section through my improved carbureter, the interior valve being in elevation. Fig. 2 is a transverse section on the line 2--2 of Fig. 1. Fig. 3 is a fragmentary perspective view of a portion of the perforated screen.

Corresponding and like parts are referred to in the following description and indicated in all the views of the accompanying drawings by the same reference characters.

Referring to these figures 2 designates the body of the carbureter, having the general shape of a bowl and inclosing the carbureting chamber 3. The upper portion of the body of the carbureter is provided with the outlet pipe 4 which is to be connected to the engine in any suitable and desired manner. The bottom of the carbureter is provided with inlet openings 5, these inlet openings 50 being arranged around a central annular hub 6, the outer face of which is upwardly and centrally inclined. This hub 6 is provided with the tapering bore 7 to receive an inlet valve, as will be later described.

The hub 6 extends down below the bottom

of the carbureter, as at 8, and is connected in any suitable manner to an inlet pipe extending from a source of gasoline. The inlet openings 5 are arranged radially, as before stated, and extend downward and outward from the central hub. The upper and lower faces of the inlet ports or openings 5 are substantially parallel to each other and upwardly and inwardly inclined, the upper face of each opening or port extending to the circumference of the lower end of the carbureter, while the lower face of each port extends slightly beyond the upper and inner edge of the upper face. This permits the air to enter the carbureter with requisite ease but at the same time, because of the fact that the openings do not extend directly downward, the vapor will not be likely to escape from the air inlet openings.

The carbureting chamber 3 has a cylindrical wall up to a point nearly level with the outlet pipe and is there provided with an annular shoulder 9. Above the shoulder 9 the wall of the carbureter is provided with an annular recess 10 which extends entirely around the carbureter and merges into the bore of the outlet pipe 4. The inner extremity of this outlet pipe is flared, as at 11, so as to provide for this gradual emergence of the annular space 10 into the bore of the outlet pipe, thus permitting an easy passage of the mixture from the annular chamber or inner space 10 into the outlet pipe, which would not be the case were there an angular junction at the point where the outlet pipe 4 joins the annular chamber.

Supporting the chamber 3 and resting upon the shoulder 9, is an annular screen 12 which may be made of perforated sheet metal, of wire gauze or any other suitable perforated or reticulated material. This annular screen rests upon the shoulder 9 and fits snugly against the wall of the carbureter above and below the chamber 10 and extends entirely across the annular chamber or space 10 so that the mixture formed within the carbureter cannot get into the annular chamber or space 10 without passing through the meshes or perforations of the screen. As illustrated, the screen is composed of sheet metal provided with perforations 13. I do not, however, wish to be limited to this.

In order to provide for an easy removal of the screen 12, the upper edge of the

screen is formed with inwardly extending flanges or lips 14 forming finger holds whereby the screen may be easily lifted out of its position or inserted within the carbureting chamber. These flanges also form a means whereby the screen is held firmly in place by the cover of the carbureter.

Preferably located within the outlet pipe 4 is the throttle valve 15, of any ordinary construction and shown as having a stem 17 extending to the exterior of the pipe 4 and being there provided with a handle 16 whereby the throttle valve may be adjusted to more or less cut off supply to the engine.

18 The cover of the carbureter consists of a plate 18 adapted to rest upon the upper end of the carbureting chamber 2 and having a central depressed portion 19 threaded to engage in the upper internally threaded end of the carbureting chamber and rests upon the flanges 14, thus holding the screen in place. This cover is formed with a central opening 21 and also with a bridge 20 extending over the opening and forming a handle whereby the cover may be easily manipulated. Passing through the bridge 20 is an adjusting screw 22 provided with a lock nut 23.

Located within the carbureter is a spreader disk 24 having an annularly arranged series of perforations 25, this disk being provided on its under side with a centrally disposed, tapered valve 26 which is adapted to engage a seat 7 of the hub 6 and control the passage of gasoline through the bore of the hub. Located between the disk 24 and the valve 26 is a flaring portion 28 which operates to divert the combined air and gasoline outwardly and upwardly and that coacts with the air inlet passages 5 to produce their thorough mixing and commingling.

It will be noted that the air passages are relatively wide at their outer ends, as shown by dotted lines in Fig. 2 and converge toward the hub 6 and are likewise inclined upwardly, so that the air in passing inwardly is slightly compressed and caused to move upwardly against the inclined outer face of the hub and against the outwardly and upwardly inclined surfaces of the member 28 and meets the inflowing gasoline and is thereby thoroughly mixed and intermingled and passes upwardly over the disk 24 and through the apertures 25. By this means the action is materially improved and the combined gasoline and air placed in the best possible condition to be vaporized and discharged through the screen 12. This is an important feature of applicant's device and materially increases its efficiency and utility.

When the valve 26 is down in its lowest position, the bore of the hub 6 is closed, and when the valve is raised upon the indraft 65 of the engine, gasoline will pass up through

the seat 7 and into the carbureting chamber to an extent depending upon the lift of the valve.

The disk 24 is provided with the valve stem 27 which extends up through the opening 21 and projects slightly above the top of the upper face of the cover 18. The adjusting screw 22 may be adjusted to limit the upward lift of the valve and its stem 27. When the adjusting screw 22 is turned down to its full extent, it will positively hold the valve closed upon the tapered seat in the hub 6. By turning the screw upward, the valve may have a limited lift, depending upon the extent to which the screw 22 is turned upward. The cover 18 may be held upon the carbureter in any suitable manner, but preferably by being threaded therein, as shown.

The operation of my invention is obvious from what has before been stated. Upon each indraft of the engine the valve 26 will be lifted, permitting the inlet of gasoline through the bore of the hub 6. At the same time air is drawn in through the openings 5. The air and gasoline pass upward around the disk or spreader 24 and through the openings 25, being somewhat mixed in the operation, and pass up into the upper portion of the casing where the mixed gases are drawn through the perforations or reticulations in the screen 12 and into the annular space or chamber 10. This causes the thorough and complete mixture of the gasoline and air before it passes into the outlet tube 4, the passage of gas through the outlet tube being of course controlled by the valve 15.

It will be seen that the proportion of gasoline to air may be controlled by adjusting the screw 22 so as to control the lift of the valve 26. When it is desired to clean the interior of the carbureter, it is only necessary to remove the cap or cover 18, whereupon either the valve may be removed, or the screen 12 taken out through the opening at the top of the carbureter. By removing the screen, it is possible to clean the interior surface of the carbureting chamber or replace the screen 12 or the valve by a new screen and valve.

My invention is simple, cannot get out of order, has no complicated parts requiring constant repair and adjustment, and does not require to be removed from the engine in order to be cleaned.

What I claim is:

1. In a carbureter, a casing having a discharge opening at the upper end and a gasoline inlet at the lower end, said lower end of the chamber being further provided with a plurality of radially disposed passages converging toward the inlet and inclining inwardly and upwardly, a valve engaging the inlet, a perforated disk within the chamber, and a flaring member between the valve

and disk, said converging air passages and flaring member coacting to cause the air and gasoline to commingle before passing around and through the disk.

- 5 2. In a carbureter, a casing open at the top and having a lateral discharge opening near the upper end and a gasoline inlet at the lower end, said casing being further provided with a plurality of air openings in its lower end, and laterally enlarged near the upper end to form an annular extension to the casing and into which extension the outlet merges, a valve for said inlet, a perforated disk connected to said valve, an annular screen within the casing and forming the inner wall of the extension, said screen having a plurality of inwardly directed lips, and a closure for the upper end of the casing and engaging upon said lips and holding the screen in position.
- 10 3. In a carbureter, a casing open at the

top and having a lateral discharge opening near the upper end and a gasoline inlet at the lower end, said casing being further provided with a plurality of radially disposed air openings in its lower end and converging toward the inlet and inclined inwardly and upwardly, a valve engaging the inlet, a perforated disk within the chamber, a flaring member between the valve and disk, a closure for the open upper end of the casing and provided with an upwardly directed bridge, an adjusting screw operating through said bridge, and a stem rising from said disk and terminating within the path of said screw.

In testimony whereof, I affix my signature in presence of two witnesses.

MICHAEL E. MALLO. [L.S.]
